UNITED STATES PATENT OFFICE.

GEORGE J. RATHBUN, OF TOLEDO, OHIO, ASSIGNOR TO INGERSOLL-RAND COMPANY, OF JERSEY CITY, NEW JERSEY, A CORPORATION OF NEW JERSEY, AND THE RATHBUN-JONES ENGINEERING COMPANY, A CORPORATION OF OHIO.

GAS-ENGINE-DRIVEN AIR COMPRESSOR.

Application filed November 23, 1925. Serial No. 70,943.

This invention relates to engines and with respect to its more specific features to couplings for direct connected engines and pumps or compressors.

- 5 The invention has for its object to eliminate the necessity of cross heads as a coupling means between the engine as for instance a combustion engine and a pump or compressor directly connected thereto.
- 10 Pumps or compressors which are double acting may be driven by a single acting engine such as an internal combustion engine if a fly wheel is provided for the engine to maintain the operation of the compressor.
- 15 during those strokes of the engine during which power is not produced. It is customary in connecting the pump or compressor to the engine to employ a cross head attached to the piston of the engine to which the connecting rod to the fly wheel shaft and the rods to the pump or compressor are attached. Direct tie rods from the cross head to the compressor are an advantage since they eliminate a cross head attached to the piston 20 rod of the compressor and thus shorten the coupling. Heretofore, however, the cross head for the engine has not been eliminated since with the usual arrangement of drive shaft and crank it has not been possible to connect the tie rods directly to the piston rod of the compressor and directly to the piston of the engine without interfering with the action of the crank or connecting rod. For instance, with the tie rods 25 connected to the engine piston at points diametrically opposed, one of the rods must be placed above or below the drive shaft while the other rod will then be found to lie in the path of the connecting rod. By 30 this invention the shaft to which the connecting rod of the engine is attached is lowered so that while the inner tie rod may be placed to just clear the shaft, the outer tie rod which lies outside of the crank pin 35 will lie substantially opposite the center of the shaft or nearly so. In this manner tie rods of the proper form may be provided to connect the piston rod of the compressor directly with the piston of the engine without the use of a cross head for the engine and without interfering with the fly wheel shaft or its crank and connecting rod.

Material practical advantages are afforded by this arrangement. The entire

assembly of compressor and driving engine 55 is greatly shortened since the connecting rod from the engine piston to the fly wheel shaft may be directly connected on a wrist pin in the engine piston, thus saving the expense of a long bed plate for the installation and the expense of a cross head.

Other objects and advantages of the invention will be in part obvious and in part pointed out hereinafter.

The invention will be more clearly understood by reference to the following description taken in conjunction with the drawings in which

Figure 1 is a horizontal section through an engine and compressor directly connected 70 in accordance with the practice of the invention,

Figure 2 is a vertical section through the engine showing the location of the drive shaft and the relative position of the tie 75 rods, and

Figure 3 is a vertical cross section through the tie rods looking in the direction of the driving shaft.

Referring to the drawings there is shown 80 a portion of the cylinder A of an internal combustion engine having a piston B which is adapted to reciprocate within the cylinder A to drive a piston C of a compressor having a cylinder D. As is usually the case 85 with an internal combustion engine the piston D is single acting; that is to say, power is developed on its forward stroke only. A fly wheel (not shown) is provided mounted on a suitable shaft E adapted to revolve in 90 bearings F mounted in any desired manner on a bed G. The shaft E is rotated by means of a connecting rod H attached by means of a wrist pin J to the piston B. The connecting rod H is suitably journaled 95 on a crank pin K of the shaft E.

The piston C is preferably double acting and is therefore provided with a piston rod L reciprocating through a suitable stuffing box O in the head of the cylinder D.

In order to couple driving engines, such as the internal combustion engine as above described, with a compressor, it has often been the practice heretofore to provide two cross heads, one operated by the piston B 105 and the other connected with the piston rod L. The cross head associated with the piston B was provided with a connecting rod

of the same general type as the connecting rod H and a somewhat similar connecting rod was attached to the cross head of the piston rod L and the other connecting rod 5 to transmit the driving force to the compressor piston. Later, the cross head associated with the piston rod L was eliminated and also the connecting rod associated therewith by connecting the cross head of the 10 driving engine directly to the piston rod L by rigid rods. This construction shortened the distance between the cylinder of the driving engine and the cylinder of the compressor and provided a more compact assembly, and in addition eliminated one of the 15 expensive cross heads. A further reduction in the cost and a more compact arrangement is gained by eliminating the cross head associated with the driving engine, but this 20 has not been practical because the lugs connecting the piston of the driving engine with the piston of the compressor could not be placed so as not to interfere with the throw of the crank for the fly wheel shaft 25 in the arrangement hitherto provided.

As shown in Figure 1 it is desirable that the rods P, connecting the piston B of the driving engine with the piston C of the compressor, be diametrically opposite with 30 respect to the axis of the piston B in order to avoid eccentric loading of that piston. In order to prevent the outer rod P from interfering with the rotation of the connecting rod H by this invention the drive 35 shaft E is dropped so that the outer rod P will lie in approximately a horizontal plane through the axis of the shaft E. In this position the inner rod P will lie over the end of the shaft E with a slight clearance

therebetween. As the rods P reciprocate 40 they will not interfere with the crank pin K or connecting rod H and may be spaced sufficiently close together to extend within the cylinder A for connection with the piston B. 45

Any suitable connection between the rods P and the piston B may be employed. In this embodiment the rods P are provided with flanged ends Q and the piston B is suitably flanged as at R. Studs S passing 50 through the flanges Q and R attach the rods P securely to the piston B. The rods P are attached to the piston rod L by means of a cross piece T secured by a nut U to the end of the piston rod L and provided with apertures through which the ends of the rods P 55 pass and are bolted by means of nuts V.

I claim:

A driving connection apparatus for direct connected driving engines and reciprocating compressor, comprising, a fly wheel crank shaft between the engine and the compressor cylinders and below their axes, a connecting rod journaled in the engine piston for driving said crank shaft, a single pair of rods 60 directly attached to the piston of said driving engine and on opposite sides of the shaft crank, one of said rods being disposed over the crank shaft, the other said rod being beyond the crank and below the piston axes, and in the plane of said crank shaft axis, 65 and a cross piece joining the ends of the pair of said rods and attached to the compressor piston rod. 70

In testimony whereof I have signed this 75 specification.

GEORGE J. RATHBUN.
